MOTORCYCLE FAIRING

Paul R. Jones and Harold H. Larsen, Long Beach, Calif.,
assignors to Bates Industries, Inc., Long Beach, Calif.,
a corporation of California

Filed Feb. 6, 1969, Ser. No. 15,664

Term of patent 14 years

Int. Cl. D12—14

U.S. Cl. D90—1

Fig. 1

Fig. 2

Fig. 3

Fig. 4

Fig.6

Fig.5

FIG. 1 is a perspective view of a motorcycle fairing showing our new design;

FIG. 2 is a front elevational view thereof;

FIG. 3 is a right side elevational view thereof, the left side elevational view thereof being a mirror image and therefore omitted;

FIG. 4 is a bottom plan view thereof;

FIG. 5 is a rear elevational view thereof; and

FIG. 6 is a top plan view thereof.

We claim:

The ornamental design for a motorcycle fairing, substantially as shown and described.
